Primary Examiner — Brian N Vinson(74) *Attorney, Agent, or Firm* — Pearne & Gordon LLP(57) **CLAIM**

The ornamental design for a mail and key organizer, as shown and described.

DESCRIPTION

FIG. 1 is a perspective view of a mail and key organizer showing our new design;

FIG. 2 is a front elevational view thereof;

FIG. 3 is a rear elevational view thereof;

FIG. 4 is a side elevational view thereof;

FIG. 5 is a top plan view thereof; and,

FIG. 6 is a bottom plan view thereof.

The broken-line disclosure in the views is understood to represent unclaimed portions of the article in which the claimed design is embodied.
